Primary Examiner — T Chase Nelson*Assistant Examiner* — Mary Claire Ramirez(74) *Attorney, Agent, or Firm* — Gokalp Bayramoglu(57) **CLAIM**

The ornamental design for a waterproof camera cover, as shown and described.

DESCRIPTION

FIG. 1 is a perspective view of a waterproof camera cover showing my new design;

FIG. 2 is another perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The broken lines shown in the drawings depict portions of the waterproof camera cover that form no part of the claimed design.

1 Claim, 8 Drawing Sheets(56)
